UNITED STATES PATENT OFFICE.

SAMUEL S. STOLP, OF MANSFIELD, OHIO, ASSIGNOR TO THE OHIO BRASS COMPANY,
OF MANSFIELD, OHIO, A CORPORATION OF NEW JERSEY.

ELECTRICALLY-OPERATED TRACK SWITCH.

Application filed December 12, 1923. Serial No. 620,152.

To all whom it may concern:

Be it known that I, SAMUEL S. STOLP, a citizen of the United States of America, residing at Mansfield, in the county of Rich-
5 land and State of Ohio, have invented cer-
tain new and useful Improvements in an
Electrically-Operated Track Switch, of
which the following is a specification.

My invention relates to electrically and
10 automatically operated track switches.

One object of my invention is to produce
a system in which the track switch
tongue may be operated from a car by the
operator applying "power on" or "power
15 off" the motors as hereinafter described.

Another object of my invention is to pro-
vide a system which will prevent the burn-
ing out of the mechanism for operating the
switch tongue.

20 Another object of my invention is to pro-
duce a system which will supply current to
the track switch operating mechanism for a
predetermined time regardless of the posi-
tion of the trolley wheel or current collector
25 with respect to the system.

A still further object of my invention is
to provide a system which, after having
been properly operated, cannot be changed
by the same car under conditions hereinafter
30 described.

35 A still further object of my invention is
to provide a system which will avoid the
breaking of any currents by the current col-
lector which may be of sufficient magnitude
to cause a destructive arc.

In the drawings accompanying this speci-
fication:

Fig. 1 is a schematic view showing the car
circuits taken into account in the described
40 operation of my invention.

Fig. 2 is a schematic drawing showing the
various parts and circuits composing my in-
vention in a normal condition, the switch
45 tongue 4, however, may be in any of its op-
erable positions.

Fig. 3 is a schematic drawing showing the
relation of the parts the instant the current
collector on the car comes into operative re-
lation with the system with "power off".

50 Fig. 4 is a schematic drawing showing the
relation of the parts composing my system
after the current collector has come into op-
erative relation with the system for a pre-
determined length of time with "power off".

Fig. 5 is a schematic drawing showing the 55
arrangement of the parts when the current
collector comes in operative relation with the
system with "power on".

I depend for the operation of my system
upon the well known "power on" and "pow- 60
er off" the motor principle in which a col-
lector W mounted upon a car engages a con-
tact pan P with "power off" the motors to
operate the switch in one direction, usually
the "straight ahead" position and in which 65
the collector engages the pan P with "pow-
er on" to operate the switch tongue in the
opposite direction, usually the "curve" di-
rection. A car is usually provided with
heaters H, lights L and air compressors F, 70
also motors M and a controller C operated
by the car operator controlling the current
to the motors. The current collector W is
mounted upon the car by the trolley pole
T. The current flowing through the ap- 75
paratus H, L and F is not under the control
of the controller C, and as this current may
amount to considerable I take this fact into
consideration in designing certain parts of
the system, as hereinafter described. When 80
the controller C in the "off" position no cur-
rent will flow through the motors M, but
when the controller is in the "on" position a
heavy current will flow through the mo-
tors M.

85 Referring to Fig. 2 the contact pan P
is mounted in fixed relation to the trolley
conductor 1 and comprises two parallel con-
tact members 2 and 3 which are normally
insulated from each other, one being elec-
trically connected to the trolley conductor 90
1 and the other normally out of electrical
engagement with the trolley conductor. The
contact members are so arranged that they
may be bridged by the current collector and
when so bridged the collector will be out 95
of engagement with the trolley conductor. When
the collector engages the contact members 2 and 3 the member 3 is electrical-
ly connected to the trolley conductor 1 and
current is free to flow through the collector
W, trolley pole T and the other car circuits 100
to ground. If the collector engages the pan
with "power on" current will flow through
the motors M. If the collector engages the
pan with "power off" no current will flow
through the motors M. I employ an elec-
trically operated track switch S having a
105

switch tongue 4, two operating solenoids 5 and 6, a plunger 7 and a connecting rod 8. The solenoids 5 and 6 have one terminal connected to a common ground connection 9. When the solenoid 5 is energized the plunger 7 is drawn inwardly and being connected to the switch tongue 4 by the rod 8, the tongue is moved to the "straight ahead" position as shown in Fig. 3, and when the solenoid 6 is energized the plunger 7 is drawn outwardly and the switch tongue is moved to the "curve" position as shown in Fig. 2.

I also employ an electrically operated switch A having a coil 10, usually of heavy wire, as it must conduct current to the motors M when the car engages the pan with "power on", and also if the car stands with a collector in engagement with the pan P and then starts. One terminal of the coil 10 is connected to the trolley conductor 1 by the conductor 11 and the other terminal is connected to the contact member 2 by the conductor 12. The number of turns in the coil 10 is so adjusted that the auxiliary car currents in the apparatus H, L and F will not sufficiently energize the coil 10 to raise the arm 13, but will be sufficiently energized by the current flowing through the motors M to raise the arm 13.

The switch A is provided with two contacts 14 and 15 and the contact 14 is normally in engagement with the arm 13. From the contact 14 to the remaining terminal of the solenoid 5 extends the conductor 16. From the contact 15 to the remaining terminal of the solenoid 6 are the conductors 17 and 18 with a holding coil 19 interposed in series therewith so that when current flows through the solenoid 6 the coil 19 will be energized sufficiently to hold the arm 13 in engagement with the contact 15 as long as current flows through solenoid 6 regardless of whether current continues to flow through the coil 10.

I also employ electrically operated switches B and C. The switch B is provided with a coil 20 and the switch C is provided with a coil 21. These coils, as well as the coil 10, are provided with a magnetic core although the coils may be provided with a movable core secured to the armatures thereof if desired. One terminal of each coil 20 and 21 is connected together by the conductors 22 and 23. The other terminal of the coil B is connected to the contact member 3 by the conductors 24 and 25 and the remaining terminal of the coil 21 is connected to the ground G by the conductor 26. Switches B and C are provided with normally open arms 27 and 28 respectively. The switch B is provided with two contact members 29 and 30. The contact member 29 is connected to the switch arm 13 by the conductor 31. The switch C is provided

with a contact 32 which is connected to the contact 30 by the conductors 33 and 34. The arm 27 is connected to the trolley conductor 1 by the conductor 35. A conductor 22 is connected to the arm 28 by the conductor 36 and the conductor 33 is connected to the conductor 25 by the conductor 37. The conductors 32, 36, 33, 37 and 25 form a shunt about the coil 20 when the arm 28 is closed or in engagement with the contact 32.

When the contact members 2 and 3 are bridged by a collector with "power off" current flows from the trolley conductor 1 through the coil 10 and its connections, through the current collector to contact member 3 and from there through the conductors 24, 25, 22, 23 and 26 to ground, simultaneously energizing the coils 20 and 21 which are of relatively high resistance so as to give a small current flow. As soon as the coils 20 and 21 are energized the arms 26 and 28 are raised into engagement with their respective contacts. Current will now flow from the trolley conductor 1 into the circuit 31 and from there through the solenoid 5 to ground as the switch 13 is in engagement with contact 14 unless the coil 10 is sufficiently energized to pick the same up. Current flowing through the solenoid 5 will draw the plunger 7 inwardly and the switch tongue 4 to the "straight ahead" position. I prefer to adjust the armatures of switches B and C such that the armature 27 will close on its contacts first thereby directing current into the switch S as soon after the collector engages the contacts as possible. As soon as the arm 28 engages its contact 32 a short circuit is placed about the coil 20, as already explained, and the coil 20 is deprived of current, but the current still flows through the coil 21. On the de-energization of the coil 20 the armature 27 will open, cutting off the flow of current to the switch S. The switch B is provided with a time lag factor first, due to the fact that it is energized and then short circuited and also by the proper spacing of the arm 27 with respect to its core when in the raised position, or I may employ a copper or brass sleeve about the coil to retard the release of the arm 27, as is well known, or I may employ other means to give the opening of the arm 27 a time lag so as to permit the flow of current to the switch S for a sufficient predetermined time to fully energize the solenoids 5 and 6.

The circuit 34 also furnishes a current to the coil 21 to maintain the arm 28 closed as long as the arm 27 remains closed. If the collector should pass over the pan at a very rapid rate and before the time for the arm 27 to open, the circuit 34 would conduct current to the coil 21 from the trolley conductor 1 by way of the switch B and maintain the switch C closed until the

switch B opens. If in passing over the pan P the car operator should unintentionally change his controller to "power on" before the switch B had opened the arm 13 would be brought into engagement with the contact 15 and a false operation of the switch S brought about, but with the circuit leading from the trolley conductor 1 by way of the conductor 35, switch B, conductors 34, 37 and 24, an additional path will be provided for supplying current to the car other than the path through the coil 10 and the current through the coil 10 would be reduced below an amount necessary to operate the coil 10 and a false operation of the switch S would not take place.

In other words, the coil 10 would be substantially short circuited. If the car operator desires to go "straight ahead" when approaching a switch, he throws his controller to "power off" with the intention of coasting over the contact pan P which is placed in advance of the switch S. When the collector engages the pan P the coils 20 and 21 are energized and the switches B and C closed and current will then flow through the solenoid 5 to ground, energizing the same and drawing the plunger 7 inwardly and the tongue 4 to the "straight ahead" position, all as shown in Fig. 3. Should the operator come to a stop with the collector upon the pan the parts will assume the position shown in Fig. 4 after a predetermined time, that is, the switch B will open, and the switch C will remain closed and current will be cut off from the switch S. When the operator starts his car, however, current will flow through the coil 10, energizing the same and picking up the armature 13, but the switch B is not affected, therefore current will not flow through the switch S to change the same. The switch B will remain open as long as the switch C remains closed. As soon as the collector has left the pan P the switch C will open, returning the system to normal as shown in Fig. 2.

If the car operator desires to take the "curve" he will pass the pan with "power on" and when the collector engages the pan the coil 10 will be energized thereby bringing the arm 13 into engagement with the contact 15 and at the same time the switches B and C will be closed and current will flow through the solenoid 6, energizing the same, drawing the plunger 7 outward and moving the switch tongue 4 to the "curve" position, all as shown in Fig. 5. If the collector has not passed the pan by the time set for the switch B to open, the same will open, however, and remain open as long as the switch C remains closed.

The holding coil 19 operates to maintain the arm 13 in engagement with the contact 15 so that current will flow through the coil

6 for a predetermined time should the operator turn his controller to "power off" before he has passed the pan. As the arm 13 cannot drop until the switch B is open, a false operation of the switch cannot take place should the operator inadvertently move his controller, as just explained.

It will be evident to those skilled in the art that various modifications may be made in the arrangement of the parts herein described, but which will still fall within the scope of my invention.

I claim—

1. A switch operating system comprising in combination, a trolley conductor, a contact pan to be engaged by a current collector, an electrically operated track switch, a switch A to control the direction of movement of the track switch, a switch B to control current flow to the track switch and normally open, a switch C to control the opening of the switch B, windings on the switches B and C connected in series and having connections to the pan and to the ground for operation when the collector engages the pan, a divided circuit from the trolley conductor to the track switch controlled by the switches A and B, a normally open circuit controlled by the switch C to shunt out the switch B after it has closed. 95

2. In a switch operating system, the combination of an electrically operated track switch, a switch operating circuit, a circuit changer to direct current into the track switch to automatically control its direction of operation, an electrically operated switch provided with an operating coil to control the circuit and electrically operated means provided with an operating coil in series with the other coil to shunt out the control switch. 100

3. In a switch operating system, the combination of an electrically operated track switch, a trolley conductor, a contact pan, a normally open circuit connecting the trolley conductor and the track switch, a normally open switch having a time lag in opening to control the said circuit and having operating means connected to the pan for operation in closing the said circuit and electrically operated means having its operating means in series with the operating means of the normally open switch to shunt out the said normally open switch after it has closed. 110

4. In a switch operating system, the combination of an electrically operated track switch, a trolley conductor, a contact pan provided with a pair of contact members to be engaged by a current collector, a normally open circuit deriving current from the trolley conductor and connected to the track switch, an electrically operated switch to close the normally open circuit and means automatically operable to shunt out the said switch and provided with an operating coil, 125 130

the coil also operating to maintain the said shunt as long as the collector engages the pan.

5. In a switch operating system, the combination of an electrically operated track switch, a trolley conductor, a contact pan provided with a pair of contact members to be engaged by a current collector, a normally open circuit deriving current from 10 the trolley conductor and connected to the track switch, an electrically operated switch having a retarded release to close the normally open circuit and means automatically operable to shunt out the said switch and 15 provided with an operating coil, the coil also operating to maintain the said shunt as long as the collector engages the pan.

6. A switch operating system comprising an electrically operated track switch, a trolley conductor, a pan provided with a pair of contact members to be electrically connected when engaged by a current collector, a circuit changing relay to control a pair of branch circuits leading to the track switch, 25 a holding coil for the circuit changer deriving current from one of the branch circuits, an operating coil for the circuit changer connected between the trolley conductor and one contact member, a circuit 30 leading from the trolley conductor to the circuit chamber, electrically operated means to control the last said circuit comprising a pair of cooperating switches each having an operating coil connected in series between 35 the other contact member and the ground and operating to close the said circuit when the collector engages the pan and to open the same after a predetermined time after closing and to remain open as long as the 40 collector engages the pan.

7. In a switch operating system the combination of, contact members, a trolley conductor to be engaged by a current collector, an electrically operated track switch, a circuit to conduct current to the track switch, 45 means to control the direction of operation

of the track switch, an electrically operated circuit closer to control the said circuit and an electrically operated switch to control the first said switch and provided with an operating coil deriving its operating current first from the contact members and then from the trolley conductor while the circuit closer is closed.

8. A switch operating system comprising 55 in combination, an electrically operated track switch, circuits and electrically operated means therefor to operate the track switch to the position desired, a switch for first closing and then opening one of said 60 circuits after a predetermined time when the device is in use so that a current collector will first close said circuit and later open the same to render the track switch operative during the time the said switch 65 is closed, an operating coil for the switch and electrically operated means having an operating coil connected in series with the said coil to short circuit the said coil to render it non-effective after a predetermined 70 time.

9. A switch operating system comprising 75 in combination, an electrically operated track switch, an electrically operated means and circuits therefor to operate the track switch to the position desired, a control switch having an operating coil for first closing and then opening one of said 80 circuits after a predetermined time when the device is in use so that a current collector will first close said circuit and later open the same whereby the track switch is rendered operative during the time the said control switch is closed and means controlled by the current flowing through the said operating coil to short circuit the said coil to cause said control switch to open after a predetermined time and remain open while a car is in cooperative relation to the 85 system.

In testimony whereof I affix my signature.

SAMUEL S. STOLP.
